Patented July 3, 1917.

UNITED STATES PATENT OFFICE.

JOSEPH LOISELLE, OF HIGH RIVER, ALBERTA, CANADA, ASSIGNOR OF ONE-HALF TO
ALEC ADDINGTON BALLACHEY, OF HIGH RIVER, ALBERTA, CANADA.

HARNESS-SEWING MACHINE.

1,232,344.

Specification of Letters Patent.

Patented July 3, 1917.

Application filed November 18, 1915. Serial No. 62,217.

To all whom it may concern:

Be it known that I, JOSEPH LOISELLE, a subject of the King of Great Britain, residing at High River, in the Province of Alberta and Dominion of Canada, have invented certain new and useful Improvements in Harness-Sewing Machines, of which the following is a specification:

My invention relates to improvements in 10 harness sewing machines wherein it is customary to channel the leather on the under side thereof when in the act of stitching the several parts together in order that the channel may afterward be utilized to cover 15 the stitches on one side of the article being stitched.

An object of my invention is to produce a channeling mechanism which is adjustable to different depths of channels.

20 A further object of my invention is to afford facilities for adjustment of the channeler by varying the exposure of the knife while the machine is in actual operation.

A further object of my invention is to 25 provide means for entirely withdrawing the channeler from its operative position when desirable without the necessity of stopping the machine.

A still further object of my invention is 30 to arrange the cutting mechanism of the channeler below the surface of the base plate, thus allowing a perfectly smooth upper surface for the plate, and to so direct the channeler knife portion that it may be 35 easily removed and replaced by newly sharpened knife portions.

Figure 1 is a top view of the entire channeler;

Fig. 2 is a bottom view of the same showing the adjustable mechanism of the channeler;

Fig. 3 is an end view showing the lower adjustable mechanism of the channeler;

Fig. 4 is an end view of the same looking 45 in the opposite direction;

Fig. 5 is a perspective view of the entire channeler in position on the stitching machine;

Fig. 6 is a perspective view of the arms 50 connecting the channel cutter with the actuating mechanism;

Fig. 7 is a perspective view of the horizontal sliding block; and

Fig. 8 is a perspective view of the guide

rod which is adapted to support the sliding 55 block.

A, indicates a base plate which as shown in Fig. 5 is attached to the stitching machine in such a manner as to bring the elongated slot a' directly beneath the 60 presser foot B of the stitching machine, which presser foot operates in the usual manner.

Arranged in advance of the presser foot B and needle is a channel cutter b which 65 is adapted to effect a channel on the under side of the leather being stitched prior to its passing between the presser foot B and plate A. This channel cutter b is carried by a rock shaft b' which is arranged longitudinally of the plate A and transversely of the stitching machine. This rock shaft b' is suitably journaled in the plate by removal clips d d.

The rock shaft b' is preferably made in 75 two parts as clearly shown in Fig. 2, which will permit of the replacement of the channel cutter without affecting the cutter adjusting mechanism. c c represents the adjusting screws which are adapted to bear 80 against the outer ends of the rock shaft, thereby providing means for laterally adjusting the channel cutter.

Arranged at the inner end of the plate A is a horizontal sliding block e which is 85 carried by a horizontal guide rod h. This block e is connected through the medium of the connecting links i and j, which are attached to the sliding block by set screw f, to the rock arm m, which is in turn secured 90 to the outer end of the rock shaft b'.

The horizontal movement of the block e is effected by a thumb screw a which is rotatably secured to the plate A having its screw threaded end received within the 95 threaded portion of the block e. It is apparent that with the rotation of the adjusting screw a the cutter knife proper will be raised or lowered within the slot a', thereby increasing or decreasing as desired 100 the depth of the channel produced in the leather being stitched. This is particularly useful where the leather, as sometimes, is of varying thickness, inasmuch as it provides a means for varying the depth of the 105 channel in proportion thereto.

As at present constructed, the stationary cutters sometimes channel the leather

too deep, thereby completely severing the leather at the thin places.

From the foregoing it will be seen that I have produced an efficient and adjustable channeling mechanism which may be attached to any form of stitching machine and one which may be readily put out of commission without the necessity of stopping the machine or the removal of the cutter plate as is customary in the channel cutters as at present constructed.

It is apparent that many slight changes might be made without departing from the general scope of my invention, therefore, I do not wish to be limited to the precise structure shown and described herein, but—

I claim:

1. A channel cutter for stitching machines comprising a base-plate, a rock-shaft 20 journaled therein, a channel-cutter arranged at one end thereof, means arranged at the ends of the rock-shaft for adjusting it laterally of the base-plate, and horizontally-arranged adjusting means located at the opposite outer end of the rock-shaft for effecting the vertical adjustment of the channel-cutter.

2. A channel cutter for stitching machines comprising a base plate, a rock shaft 30 rotatably journaled therein, a channel cutter arranged at one end thereof, means for adjusting the rock shaft laterally of the base plate, a sliding block horizontally arranged upon said base plate, links connecting the block to the rotatable rock shaft, and means for imparting horizontal movement to the sliding block for effecting a vertical adjustment of the channel cutter.

3. A channel cutter for stitching machines comprising a base plate, a rock shaft 40 journaled therein, a channel cutter arranged on one end of said rock shaft, set screws arranged at either end of said rock shaft for adjusting the latter laterally of the base plate, a horizontally sliding block arranged upon said base plate, a rock arm attached to one end of said rock shaft, links connect-

ing the rock arm to said sliding block, and means for adjusting the sliding block to effect a vertical movement of the said channel cutter.

4. A channel cutter for stitching machines comprising a base plate, a rock shaft 50 consisting of two members rotatably arranged upon said base plate, a cutter arranged on one end of said rock shaft, means for laterally adjusting said rock shaft, and means for rocking said rock shaft thereby imparting a vertical movement to said channel cutter.

5. A channel cutter for stitching machines comprising a base plate, an elongated slot therein, a rock shaft journaled on the under side thereof, a channel cutter arranged on one end thereof adapted to be 65 received within said elongated slot, means for adjusting the cutter laterally within said slot, a horizontal sliding block arranged upon said base plate, links and a rock arm connecting said rock shaft and sliding block together, and means for imparting a horizontal movement to the sliding block for effecting a vertical movement of the channel cutter.

6. A channel cutter for stitching machines comprising a base plate, an elongated slot arranged transversely at one end, a rock shaft arranged longitudinally of said base plate, a channel cutter attached to one end thereof, a rock arm attached 70 to the other end thereof, set screws engaging the outer ends of the rock shaft for adjusting the rock shaft laterally of the said base plate, a horizontal sliding block arranged transversely upon said base plate, 75 links connecting the said rock arm and sliding block, and an adjusting screw journaled upon said base plate in engagement with the sliding block for imparting a horizontal movement, which in turn is adapted to raise 80 and lower the said channel cutter.

In testimony whereof I affix my signature.

JOSEPH LOISELLE.
